[57] CLAIM

The ornamental design for a reflector fluorescent lamp,
as shown and described.

DESCRIPTION

FIG. 1 is a top perspective view of a reflector fluorescent lamp showing my new design;

FIG. 2 is a front elevational view thereof on a reduced
scale, the rear being a mirror image;

FIG. 3 is a top plan view thereof on a reduced scale; and

FIG. 4 is a bottom plan view thereof on a reduced scale.
The faceting on the top surface of the lens is partially
shown for convenience of illustration, it being under-
stood that the faceting is continuous over the area delin-
eated in FIG. 3.
